ELASTIC FLUID TURBINE AND METHOD OF OPERATING THE SAME

Application filed May 5, 1928. Serial No. 275,416.

The present invention relates to elastic fluid turbines and more particularly to elastic fluid turbines designed to operate at variable speeds and to a method of operating such turbines.

A common method of controlling the power of a turbine in accordance with the load placed thereon consists in adding or cutting out one or more nozzles for the more substantial changes in the load, smaller variations being taken care of by a throttling of one or more of the nozzles. Such a method is reasonably satisfactory for a constant speed load, such as an electric generator, but is open to the disadvantage of a considerable loss in efficiency when the load is such as to require operation of the turbine at different speeds. An example of the condition of variable speed operation may be found in the auxiliary turbines used in power plant operation for driving the mechanical draft fans. As the load on the station varies, the demand for draft likewise changes and the draft is ordinarily adjusted by running the fans at variable speeds. Inasmuch as the usual turbine employs identical nozzles which will operate most efficiently at only one speed, there is a decrease in efficiency and a waste of energy when the turbine is called upon to drive the fan at any other speed than that particular one for which the turbine nozzles are best adapted.

The object of the present invention is to devise an elastic fluid turbine which will operate with maximum efficiency at any one of a number of different speeds.

With this object in view, the principal feature of the present invention comprises a turbine having a plurality of individual nozzles, each for a different speed and each constructed and designed in such a manner as to introduce the fluid to the turbine with maximum efficiency at its own particular predetermined speed.

In order to secure such maximum efficiency the nozzle must bear a certain definite angular relation to the bucket walls of the rotor, and this angular relation will depend upon both the steam velocity at the nozzle and the bucket velocity past the nozzle. Thus, for

low speed operation, the difference in inclination between the low speed nozzles and the rotor buckets is small, while the nozzles which are to be supplied with greater amounts of steam but at the same velocity for higher rotational speeds have increasing inclinations from the rotor buckets. The desired angular relation is such that at the given steam velocity and rotor velocity the steam will enter the bucket without abrupt change in its direction of flow. The side walls of the bucket, therefore, at the steam receiving end are so inclined to the axis of the nozzle, taking into consideration the direction and velocity of the steam and the movement of the rotor, as to make such side walls in effect parallel to the steam flow. Or expressed in another way, the angle of inclination between the bucket velocity and the relative steam velocity should be the same as the angle of inclination of the bucket.

Since the same buckets in the rotor are used for all the nozzles and obviously cannot be adjusted or changed to suit different conditions of steam velocity and rotor speed, the nozzles themselves must be so designed as to satisfy the required conditions.

The nozzles, which are formed with the usual reversing or re-directing buckets are preferably arranged in sets, the separate nozzles of each set being identically constructed for operation with maximum efficiency at a single selected speed. When it is desired to run the turbine at a selected speed, one only of the nozzle sets is supplied with fluid, the remainder being entirely cut out of operation. In order to obtain speeds intermediate to the selected speeds, the turbine is supplied with fluid through nozzles of more than one set. Although this action necessarily entails some loss of efficiency, the deviation from best operating conditions is small if a sufficient number of separate nozzle sets are employed.

In the accompanying drawing, Fig. 1 is a diagrammatic elevation partly in section of the preferred form of the turbine and the fluid supply controlling means; Fig. 2 is a detail view, partly in section, of one of the nozzle sets; Fig. 3 is a vector diagram explanatory of the operation of the nozzles in

the different sets; and Fig. 4 is a similar diagram showing the operation of the reversing buckets of a single nozzle.

The illustrated embodiment of the invention comprises a turbine, indicated generally at 4, to which steam is supplied through the pipe 6, and which operates the variable speed fan 8. The turbine 4 is provided with four nozzle sets indicated generally at 10, 12, 14 and 16, being adapted respectively for low speed, two intermediate speeds, and high speed operation.

Each nozzle set comprises four nozzle heads 20, each having a nozzle 22 and a plurality of reversing buckets 23, 24 and 25. All of the nozzles are of the same expansion ratio, since they receive the steam at the same pressure but are arranged at different inclinations from the rotor buckets. Each nozzle of the set 10 is arranged for delivering a small quantity of steam for low speed operation and is placed at a slight inclination from the rotor buckets 26. See Fig. 2. The nozzles of the set 12 are somewhat larger and are placed at a slightly greater inclination for higher speed of rotation, and the nozzles of the sets 14 and 16 are progressively larger and have greater inclinations. The inclinations of the nozzles are diagrammatically indicated by the dotted lines *a*, *b*, *c*, and *d* of Fig. 1. The sizes of the nozzles of the several sets will depend upon the amount of working fluid which each set has to supply for satisfying the load demands at the particular speed of operation of that set. All of the nozzles are identical as to expansion ratio (i. e. ratio of mouth area to throat area), and the nozzles of each particular set are of the same inclination and preferably of the same size.

The control means for connecting the nozzles with the steam supply comprises an annular distributing chamber 28 having a plurality of inwardly extending valve chambers 29, one for each nozzle, and connected to the separate nozzles by suitable conduits. The valve chambers are divided into four groups of four each, the groups being indicated at 30, 32, 34 and 36, for connecting respectively to the nozzles of the sets 10, 12, 14 and 16. Only one set of conduits is shown in the drawing, this set 40 leading from the valve chamber 30 to the nozzles of the set 10. Communication between the chamber 28 and the various depending valve chambers is controlled by valves 44 which are actuated by a cam 46 cooperating with cam followers 48 on the valve stem 50. The cam is supported on a cam shaft 54 concentric with the distributing chamber. A pressure controlled device comprising a pressure operated piston 56 communicating with the cam shaft through a rack and pinion connection 58 is shown diagrammatically in Fig. 1, being adapted for operation by the draft demands on the station. This automatic control is of any usual

or preferred form and in fact may be dispensed with if manual operation of the valves is desired.

In the preferred form of the invention, the cam is arranged to maintain four valves open at any one time, the remaining twelve valves being closed. The cam has a high part 60 of sufficient size to open four valves, the other valves being maintained closed by springs or other suitable means. When the demands on the plant are small, the four valves of the group 30 will be open, thus running the turbine at its lowest speed from the nozzles of the set 10. As the demand is increased the cam is rotated in the direction of the arrow, thereby successively cutting out nozzles of the set 10 and cutting in nozzles of the set 12. The particular positions of the valves shown in Fig. 1 are for operation on one of the nozzles of the set 10 and three nozzles of the set 12. A further rotation of the cam will open the valves of the group 32 exclusively. As the demands increase, the higher speed nozzles will be cut in until the turbine finally operates on the four nozzles of the high-speed set 16. The turbine operates at maximum efficiency at those selected speeds which call for operation from one set of nozzles alone, to the exclusion of all others, and at nearly maximum efficiency at intermediate speeds when nozzles of adjacent sets are employed.

The vector diagram of Fig. 3 illustrates the conditions for full speed and half speed operation, employing the nozzles of sets 16 and 12 respectively. In each case, the turbine is assumed to operate on the nozzles of one set only, all other nozzles being out of operation.

The absolute peripheral speed of the rotor is represented along a horizontal line. For full speed rotation, this speed is represented by the vector *oe*. At this time the nozzle set 16 is open while the remaining nozzles are cut off from communication with the steam supply. The absolute velocity of the steam is represented by the vector *fe* which makes with the vector *oe* an angle *N'*, which angle is the angle of inclination of the nozzle axis with respect to the tangent to the rotor. The relative velocity of the steam with respect to the rotor is the difference of the vectors *fe* and *oe* represented as the vector *fo* making with the horizontal an angle *R*. For most efficient operation, as already explained, this angle should be equal to the angle of inclination of the buckets with respect to the tangent.

Similarly, for half speed operation, the peripheral rotor speed is represented as the horizontal line *og*. The absolute steam velocity is *hg*, which is of the same magnitude as the vector *fe* because the steam is admitted at the same pressure and is passed through a nozzle of the same expansion ratio. The angle of inclination, however, is larger, more nearly approaching the value of the angle *R*,

and is represented as N^2 . The vector difference of hg and og is ho , which is the relative velocity of the steam with respect to the rotor and which, owing to the proper design of the nozzle with the correct angle of inclination, also makes the same angle R with respect to the horizontal. Thus in each case, the inclination of the nozzle corresponds properly with the relative velocity of the steam with respect to the rotor and the steam enters the bucket without eddying or abrupt change of flow and corresponding loss in efficiency.

Thus, in the turbine illustrated in the drawing, the inclination of the nozzles of the set 10, which are for one-quarter speed, is $1\frac{1}{2}^\circ$; that of the nozzles of the set 12, which are for one-half speed, is 3° ; that of the nozzles of the set 14, which are for three-quarter speed, is 4.5° , while the full speed nozzles have an inclination of 6° . The inclination, as given above, is the angle between the nozzle and the bucket, represented in Fig. 3 as the angle efo for the high speed nozzles, and as the angle gho for the half speed nozzles. These angles are purposely exaggerated in the diagram.

Although the relative velocity is greater in the half speed case, it does not follow that the rotor speed will be greater, because in fact, the rotor speed is determined by the load and the steam supply imparted through the particular nozzle set employed. The nozzle set used at low speed is the set 10 which employs small nozzles for the purpose of limiting the amount of steam for driving the turbine. The vector diagrams of one-quarter and three-quarter speeds are not shown in Fig. 3, but may be constructed in an exactly similar manner. The nozzle inclinations in any case will be such that when the absolute velocities of steam and rotor speed are compounded, the relative velocity will lie along the line oh .

The vector diagram illustrates the condition necessary for maximum efficiency, which condition is satisfied only when the turbine is run from the four nozzles of any one set alone, all other nozzles being cut out of operation. In other words, the turbine is then being operated at one of the selected speeds for which the particular nozzle set then in service is designed. At intermediate speeds, say, three-eighths speed, it is necessary to employ nozzles of both of the sets 10 and 12. The conditions for maximum efficiency are then not completely satisfied, because the inclination of the nozzles of set 10 is slightly too small and the inclination of the nozzles of set 12 is slightly too large to give exact velocity compounding of the absolute steam velocity with the rotor velocity. However, with provision for four selected speeds at full efficiency, the deviation from best conditions at any other speed is practically negligible.

In order to secure maximum efficiency of operation of the turbine, the reversing or re-

directing buckets of the nozzles must also be properly designed with respect to their inclinations to the rotor buckets so that the steam will be discharged from such reversing buckets into the rotor buckets without abrupt change in direction. Inasmuch as the velocity of the steam in each reversing bucket becomes progressively lower in its passage through the several buckets of the nozzle unit, these buckets are given a progressively greater inclination to the rotor buckets. The actual inclination of these reversing buckets to the rotor buckets will depend, just as does the inclination of the nozzle itself, both upon the steam velocity as it issues from the reversing bucket, and upon the speed of the rotor bucket.

In Fig. 2 is shown a nozzle set, such as the low speed set 10, comprising four nozzle units, each having the three reversing or re-directing buckets 23, 24 and 25. Bucket 23, which is next to the nozzle and receives the secondary steam as it is discharged from the rotor, has a slightly less inclination to the tangent than has the nozzle itself, because the secondary steam is at a lower velocity than the primary or nozzle steam.

Similarly the second or intermediate bucket 24 which receives the tertiary steam is still less inclined to the tangent than bucket 23, and bucket 25 which receives the quaternary steam is even less inclined than bucket 24. For the purpose of illustration the inclinations are shown in exaggerated degree.

The reversing buckets of the other sets of nozzles which operate the rotor at higher speeds would have different inclinations from those of the corresponding low speed buckets, but all would have the same characteristic of progressively smaller inclination to compensate for the reduced steam velocity, thereby securing the maximum efficiency.

In Fig. 4 of the drawing is shown a vector diagram illustrating this varying inclination of the reversing buckets of a nozzle unit. In this diagram the horizontal vector jk represents the rotor speed, the vector kl represents the absolute steam velocity from the nozzle, and the vector lj represents the relative steam velocity with respect to the rotor. The angle P represents the inclination of the rotor bucket from the tangent and the angle lkj shows the inclination of the nozzle to the tangent of the rotor.

Since the rotor velocity is the same for all the buckets of the nozzle unit, the vector jk will be the same for the several reversing buckets. The angle P of the bucket, of course, remains constant. The several vectors mk , nk , and sk represent the absolute steam velocities of discharge from each of the reversing buckets 23, 24 and 25, and the angle of inclination of each of these buckets is

represented by the angles mkj , nhj , and skj respectively.

While in the accompanying specification and drawing there is described and shown a construction in which the steam is supplied to all the nozzles at the same pressure and, therefore, the nozzles all have the same expansion ratio, the present invention is not limited thereto except where so specifically set forth in the claims, but may be embodied in a construction in which the steam is supplied to the different nozzles at different pressures. Such a construction is shown and described and claimed in my companion application of even date herewith.

The present invention contemplates in its broader features the use of a plurality of nozzles or sets of nozzles, each capable of independent use, and each designed to drive the rotor at a particular speed, the inclination of the nozzles being such that each nozzle or set of nozzles operates to drive the rotor at its own particular speed with maximum efficiency. The invention further contemplates the provision with each nozzle of one or more reversing or re-directing buckets each so inclined as to return the steam to the buckets of the rotor with maximum efficiency.

Another feature of the present invention is the operation of the turbine at speeds intermediate to the selected speeds by employment of nozzles of more than one set at a time.

Moreover, it is not necessary, although preferable, that the nozzles of each set shall be of identical inclination. It is within the purview of the present invention to employ nozzles, all of different and progressively varying inclination. With this construction, when a plurality of nozzles are supplied at one time, there will be no selected speeds at which the conditions for utmost efficiency are completely satisfied, but the deviations from best condition will be small at all speeds.

Although the invention has been described in connection with nozzle sets each having a plurality of nozzles, and although such construction is desirable from the standpoint of nicety of control, the invention is not limited to this particular arrangement, and the term "nozzle set" as used in the claims, except where it is specifically limited to a plurality of nozzles, is inclusive of a single nozzle.

Having thus described the invention, what is claimed is:

1. A variable speed elastic fluid turbine having, in combination, a rotor provided with buckets, a plurality of nozzle units constructed and arranged for operation of the rotor at different speeds, each nozzle unit comprising a nozzle and a plurality of reversing buckets, the inclination of each bucket along the path of flow of the fluid through a nozzle unit being progressively less with

respect to a rotor tangent, and means for supplying working fluid to one of the nozzle units to operate at a selected speed.

2. A variable speed elastic fluid turbine having, in combination, a rotor provided with buckets, a plurality of nozzle units constructed and arranged for operation of the rotor at different speeds, each nozzle unit comprising a nozzle and a plurality of reversing buckets, the inclination of the nozzles with respect to a rotor tangent being progressively less with the nozzles for operating at the progressively higher speeds, and the reversing bucket of each unit along the path of flow of the fluid having a progressively less inclination with respect to such tangent, and means for supplying a working fluid to one of the nozzle units to operate at a selected speed.

3. A variable speed elastic fluid turbine having, in combination, a rotor provided with buckets, a plurality of nozzles of progressively varying inclinations with respect to the buckets, and progressive control means having provision for operating the turbine from a predetermined number of nozzles, and means for operating the control means to progressively cut in nozzles of greater inclinations and to cut out nozzles of smaller inclinations while maintaining the same number of nozzles in operation for increasing the speed.

4. A variable speed elastic fluid turbine having, in combination, a rotor provided with buckets, a plurality of sets of nozzles, each set having a plurality of nozzles of the same inclination, the nozzles of different sets having different inclinations, each set having the same number of nozzles, a valve for each nozzle, and progressive control means for maintaining a predetermined number of valves open, said means having provision for progressively cutting in nozzles of larger inclinations and cutting out nozzles of smaller inclinations to increase the speed.

In testimony whereof I have signed my name to this specification.

OLIVER D. H. BENTLEY.
